GEORGE W. BEADLE, OF MONTCLAIR, NEW JERSEY, ASSIGNOR TO SINGLE SERVICE PACKAGE CORPORATION OF AMERICA, OF NEW YORK, N. Y., A CORPORATION OF NEW JERSEY.

LOCKING SLIP-CLOSURE FOR VESSELS.

1,027,233.

Specification of Letters Patent. Patented May 21, 1912.

Application filed November 23, 1910. Serial No. 593,943.

To all whom it may concern:

Be it known that I, GEORGE W. BEADLE, a citizen of the United States, residing at Montclair, in the county of Essex and State 5 of New Jersey, have invented certain new and useful Improvements in Locking Slip-Closures for Vessels, of which the following is a specification.

This invention relates to locking slip closures for vessels and has for its object to 10 produce a closure of this nature which will be simple in construction and efficient in action.

To these ends the invention consists in the 15 novel details of construction and combinations of parts more fully hereinafter disclosed and particularly pointed out in the claims.

Referring to the accompanying drawings 20 forming a part of this specification in which like numerals refer to like parts in all of the views,—Figure 1 is a longitudinal sectional view of a vessel provided with a closure made in accordance with my invention. 25 Fig. 2 is a sectional view on the line 2—2, of the parts shown in Fig. 1. Fig. 3 is a view similar to Fig. 1, illustrating a slightly modified form of closure. Fig. 4 is a plan view of the closure shown in Fig. 3. Fig. 5 30 is an enlarged detail sectional view of a portion of the closure illustrated in Figs. 3 and 4.

1, indicates any suitable body portion, 2 a bottom closure therefor, and 3 a cap closure for the top portion of the body 1. To 35 the slip closure 3 is secured by any suitable means as by a staple 4, or by adhesives a locking disk 5. This disk 5 is preferably made slightly larger than the interior of 40 the vessel proper, and then can only be inserted inside said vessel as shown by slightly dishing or flexing the disk. When flexed or dished disks such as 5 are employed in connection with very thin body portions 1, 45 and especially when said dished disks 5 are considerably larger than said body portions 1, the said body portions will upon handling be distorted into a more or less oval form, unless some means, such as the flange 50 6 of a cover is employed to prevent this distortion. Furthermore when this distortion is allowed to take place, the hold or biting action of the locking disk or plate 5 is

largely lost. It is therefore an important 55 feature of my invention to provide a bracing flange 6 in connection with my locking disk or plate 5, in order to prevent the vessel body from being distorted when subjected to the pressure of handling and to thereby cause a tighter locking action between the vessel body and the disk or plate 5.

After the parts are forced into the position shown in Fig. 1, it is evident the disk 5 will frictionally hold the cover in place, and if it is somewhat larger than the interior 60 of the vessel, said cover 3 cannot be removed except by a turning or a screwing action; and that therefore slip covers such as 3, may be firmly and readily locked to thin walled vessels such as those usually 65 made of paper stock. Since the turning action may be considerable in locking closures of this nature, I sometimes provide the cover 3 with semicircular slots 10 which 70 extend only partially through the said cover, as best indicated in Figs. 3 and 5, and I pass a staple 11 through the slots in said cover and through said locking disk or plate 5 as plainly shown in Figs. 3, 4 and 5. With such a structure a turning action upon 75 the closure 3 will cause the thinner webs 12 of the said closure to be torn or cut by the staple 11, and thereby disclose the fact that the vessel has been opened. If a great deal 80 of force is required to open the vessel, the said slots 10 will be ripped to their extremities before the closure is removed, while if a slight force is required, the slots will only 85 be torn throughout a portion of their length.

It is obvious that those skilled in the art 90 may vary the details of construction and arrangement of parts without departing from the spirit of my invention and therefore I do not wish to be limited to such features except as may be required by the claims. 95

What I claim is:

1. The combination of a vessel having flexible resilient walls; and a closure comprising a cover portion having a flanged rim adapted to tightly fit the outside of the 100 wall of the vessel, and a dished disk portion secured to said cover portion adapted to fit the interior of said vessel, said flanged rim extending along the said outside wall below the point engaged by said disk, substantially 105 as described.

2. A vessel closure comprising a flanged cover portion having grooves therein and adapted to fit the outside of said vessel; a dished disk portion adapted to fit the inside of said vessel; and fastening means passing through said grooves and said disk portion, substantially as described.

In testimony whereof I affix my signature in presence of two witnesses.

GEORGE W. BEADLE.
